Patented Aug. 31, 1926.

UNITED STATES PATENT OFFICE.

HAROLD L. BLANCHARD, OF MILLEURY, MASSACHUSETTS, ASSIGNOR TO CROMPTON & KNOWLES LOOM WORKS, OF WORCESTER, MASSACHUSETTS, A CORPORATION OF MASSACHUSETTS.

DETECTOR IN REGULARLY-MOVING TRANSFERRER.

Application filed February 8, 1926. Serial No. 86,717.

This invention relates to improvements in the form of weft detecting mechanism located in a regularly moving transferrer arm. Such devices usually employ a plunger normally in non-actuating position by some form of latch and at indication of weft exhaustion the plunger is moved to actuating position to effect a change in the replenishing mechanism when the transferrer arm rises. It is the principal object of my invention to provide a latch for the plunger so related to the latter and the detector that accidental engagement of the latch by the detector will tend to move the latch into 15 tighter holding engagement with the plunger. When insufficient weft is present, however, the detector will slide under the latch and move the same to plunger releasing position.

In co-pending application Ser. No. 78,181 filed by Hume there is shown a transferrer arm having a sliding spring pressed plunger held in non-indicating position by means of a latch pivoted on the transferrer arm and having engagement with a notch formed in the plunger. The detecting member is mounted on a lever pivoted to the transferrer arm and is so designed as to pass under the latch at substantial exhaustion of weft, continued downward movement of the transferrer arm positively unseating the latch to release the plunger. In said application the latch is pivoted in such a way that accidental engagement of the detector member with the latch prior to substantial exhaustion tends to move the latch to unlocking position with the result that faulty indication occasionally takes place.

In co-pending application Ser. No. 25,643 filed by Chevrette, the plunger is held by a spring locking latch toward which the detector can move when sufficient yarn is present, but in said application the latch is moved down by the lever which supports the detector at the time the latter moves under the latch, and said detector must therefore be so located as to be out of contact with said latch. This application, therefore, does not lend itself to the principle set forth herein, but I do retain the latch and plunger as first shown in said Chevrette application.

It is an important object of my present invention to combine the advantage of positively unlocking the plunger as in the Hume

device without the uncertainty of its operation by reversing the Chevrette device and bringing it within the range of action of the detector.

With these and other objects in view which will appear as the description proceeds, my invention resides in the combination and arrangement of parts hereinafter set forth and described in the claims.

In the accompanying drawings wherein I have shown a convenient embodiment of my invention,

Fig. 1 is a vertical section looking from the rear of the loom through a transferrer arm showing the parts associated therewith made according to my present invention, and with said parts as they are normally related when the transferrer arm is in raised position.

Fig. 2 is a fragmentary view similar to Fig. 1 showing the detector in engagement with a full bobbin,

Fig. 3 is a view similar to Fig. 2 but showing the detector in engagement with a substantially exhausted bobbin but with the transferrer arm spaced slightly above the bobbin,

Fig. 4 is a view similar to Fig. 1 but showing the parts in indicating position with the detector under the latch to release the plunger, and

Fig. 5 is a vertical transverse section on line 5—5 of Fig. 1.

Referring to the drawings it will be seen that I have provided a transferrer arm 10 having a foot 11 to engage the butt of the bobbin B and having an arm 12 extending forwardly to a pivotal mounting (not shown) for the transferrer arm. By means of mechanism not shown the transferrer arm is moved up and down as the loom operates, being given a quick downward motion when the shuttle is thereunder and being raised immediately thereafter to communicate indicating movement to the replenishing mechanism (not shown) should the bobbin give an indication for replenishment.

A lever 13 has a laterally extending lug 14 positioned for engagement with a yielding pad 15 which is normally raised in the position shown in Fig. 4 but which can be pressed against spring action by lug 14. The lever is pivoted to the transferrer arm as at 16 and the outer end thereof affords pivotal support for a detector member 17

having a yarn engaging tip 18 which is normally displaced from vertical alignment with the pivot of the member 17.

5 A plunger 19 having a shoulder 20 is slidably mounted in the transerrer arm 10 and has a reduced end 21 which passes through a web 22 of said arm 10. A spring 23 is interposed between the web 22 and the shoulder 20 and tends normally to move 10 the plunger from the position shown in Fig. 1 to the position shown in Fig. 4. The reduced end 21 is provided with a notch 24 by means of which the plunger may be held against the action of spring 23 in the position shown in Fig. 1 and said end 21 is further provided with a stop such as a cotter pin 25 which engages the outer wall of the web 22 to limit movement of the plunger under action of spring 23. The 15 matter thus far described is substantially the same as that set forth in Patent No. 1,345,508 to Ryon, and the aforesaid applications.

20 In carrying out my improvements I pivot the latch beyond and above the notch formed in the plunger. The latch 30 is provided with a substantially vertical face 31 positioned for engagement with the detector tip 18 and said latch is further provided with a detent or tooth 32 positioned to enter the notch 24. The lower portion of the latch is provided with a substantially horizontal lifting arm 33 spaced sufficiently 25 below the plunger to permit an appreciable angular movement of said latch. Said latch is pivoted on a stud 34 which extends between the walls 26 of the transerrer arm and said stud is so located that the tooth 32 lies between said stud and the detector 30 tip 18.

Under normal operation the transerrer arm will move downwardly on the detecting beat of the loom to cause engagement of the lug 14 with the yielding pad 15 and if the detector tip engages a full bobbin as indicated in Fig. 2 further downward movement thereof will be arrested and the yielding pad will be depressed. When an insufficient supply of weft for continued 45 weaving remains on the bobbin, however, the detector tip will move about its pivot 50 27 first to the position shown in Fig. 3 and then upon a further downward movement of the transerrer arm to the position shown in Fig. 4, where it will be seen that the detector tip has moved under the latch 30 to move the same angularly about the stud 34, thus moving the detent 32 from notch 24 to permit the spring plunger 19 to move to the indicating position shown 55 in Fig. 4. Upon the upward movement of the transerrer arm said plunger will give an indication to the replenishing mechanism (not shown) and will also be 60 returned to the position shown in Fig. 1.

It not infrequently happens that on the downward motion of the transerrer arm the detector 17 vibrates to such an extent that the tip 18 will strike the face 31 of the latch and tend to move the same angularly 70 about stud 34. Said stud is so placed as to be on that side of a vertical line passing through detent 32 opposite the detector, and is also on that side of the axis of the plunger which is opposite the lifting arm 75 33. Hence, whenever the face 31 is engaged by the tip the detent 32 will be moved into tighter contact with the plunger 19 and unlocking of the same will be prevented, but when the tip 18 is free to move 80 under the horizontal arm 33 of the latch, however, the latter will be moved to release the plunger. Inasmuch as the latch is disposed entirely on one side of the pivotal support 34 gravity will tend to move the 85 detent into the notch. Tension spring 35 passes through and has one end operatively attached to lever 13 while the other end is anchored to the transerrer arm as at 36 to return the lever to normal position. 90

From the foregoing it will be seen that I have provided a very simple means for releasing the plunger in detectors of the type described herein and that the latch is so pivoted that accidental contact between the 95 detector tip and the latch at such times as indication of weft exhaustion is undesirable tends only to insure a more certain locking of the latch and the plunger, but that as soon as it is proper for indication to occur 100 the latch may be moved in the opposite direction from that in which it tends to move when struck improperly by the detector tip to unlock the actuating plunger. It will also be seen that the latch moves toward 105 the detector when releasing the plunger, this motion naturally being prevented when the latch is accidentally struck by a non-indicating movement of the detector.

Having thus described my invention it 110 will be apparent that changes and modifications may be made therein by those skilled in the art without departing from the spirit and scope of the invention and I do not wish to be limited to the details 115 herein disclosed, but what I claim is:—

1. In a weft detecting mechanism for a loom, a regularly reciprocating transerrer arm, a plunger slidably mounted in the arm, a latch for the plunger having a releasable holding engagement with the plunger, a pivot about which the latch moves, and a weft detector carried by the transerrer arm and positioned for operative engagement with the latch to move the same to plunger 120 releasing position at substantial weft exhaustion, the locking engagement between the latch and the plunger lying between the detector and the point about which the latch moves as a center. 125 130

2. In a weft detector for looms having a regularly reciprocating transerrer arm, a plunger slidably mounted in the arm, a latch pivotally mounted on the transerrer arm and having locking engagement with the plunger to hold the same in inoperative position, a weft detector carried by the transerrer arm and movable into engagement with the latch, engagement of the detector with the latch prior to substantial exhaustion of the weft tending to render more certain the locking engagement between the latch and the plunger and engagement of the detector with the latch at substantial exhaustion tending to move the latch to a position to unlock the plunger. 50 55
3. In a weft detecting mechanism for looms having a regularly reciprocating transerrer arm, a plunger slidably mounted on the transerrer arm, a latch movably mounted on the arm and having locking engagement with the plunger to hold the same in inoperative position, and a detector carried by the transerrer arm and movable into engagement with the latch, engagement of said detector with the latch at such times as indication of weft exhaustion is undesirable tending to move said latch to render more certain the locking engagement thereof 60 65 70 75
- 30 with the plunger and engagement of the detector with the latch at such times as indication is desirable tending to move the latch in the opposite direction to unlock the plunger. 80 85 90 95
- 35 4. In a weft detecting mechanism for a loom having a transerrer arm movable toward and from the weft supply to be detected, a spring stressed actuating member movably mounted on the transerrer arm 40 and tending to move to operative position, a latch supported by the transerrer arm and engaging the actuating member to hold the same in inoperative position, and a weft detector carried by the transerrer arm and 45 movable at substantial weft exhaustion to engage the latch and move the same to release the actuating member, said detector when indicating having a movement a com- 50 55 60 65 70 75 80 85 90 95

In testimony whereof I have hereunto affixed my signature.

HAROLD L. BLANCHARD.
